UNITED STATES PATENT OFFICE.

OSCAR B. WELKER, OF MIDDLETOWN, CONNECTICUT, ASSIGNOR TO THE WELKER-HOOPS MANUFACTURING COMPANY, OF MIDDLETOWN, CONNECTICUT, A CORPORATION OF CONNECTICUT.

DESIGN FOR A CAP FOR GASOLINE TANKS.

Application filed July 25, 1925. Serial No. 14,226. Term of patent 14 years.

To all whom it may concern:

Be it known that I, OSCAR B. WELKER, a citizen of the United States, and a resident of Middletown, in the county of Middlesex and State of Connecticut, have invented a new, original, and ornamental Design for Caps for Gasoline Tanks, of which the following is a specification, reference being had to the accompanying drawing, forming part hereof, in which—

Figure 1 is a plan view of a cap for gasoline tanks showing my new design.

Figure 2 is a view in side elevation of the same.

I claim:

The ornamental design for a cap for gasoline tanks, as shown.

OSCAR B. WELKER.
